UNITED STATES PATENT OFFICE.

WILLIAM S. BECHTOLD, OF NEWARK, NEW JERSEY.

DESIGN FOR A JEWELRY CABINET.

Application filed September 15, 1922. Serial No. 3,734. Term of patent 7 years.

To all whom it may concern:

Be it known that I, WILLIAM S. BECHTOLD, a citizen of the United States, residing in the county of Essex, city of Newark, and State of New Jersey, have invented a new, original, and ornamental Design for Jewelry Cabinet, of which the following is a specification, reference being had to the accompanying drawing, forming part thereof, in which the figure is a prospective view of a jewelry cabinet showing my new design.

I claim:

The ornamental design for a jewelry cabinet.

WILLIAM S. BECHTOLD.
